FLUID VELOCITY GOVERNOR

Harold T. Snell, El Paso, Tex.

Application April 10, 1946, Serial No. 661,150

4 Claims. (Cl. 137—152)

1

The present invention relates to a device which is designed and adapted to govern or control the flow of gaseous fuel mixture to an internal combustion engine.

The principal object of the invention is the provision of a device of the indicated character which is operated by suction of the engine and in accordance with the amount of the air and fuel mixture flowing through the device from a carburetor to the engine as determined by the acceleration, pulling and power demands of the engine.

A further object is the provision of a device of the indicated character which enables adjustments for varying the volume of the fuel mixture according to the horsepower of the engine, and which is also of simple, effectual and substantial design.

With the foregoing, other objects of the invention will appear when the following specification is read in conjunction with the accompanying drawing, in which—

Fig. 1 is a side view showing the governor of the present invention connected in operative position between the down flow fuel mixture outlet of a carburetor and an intake manifold of an internal combustion engine, one part being removed and another part being in section to show certain features.

Fig. 2 is a horizontal sectional view taken on the line 2—2 of Fig. 1.

Fig. 3 is a sectional view taken on the line 3—3 of Fig. 2.

Referring now more particularly to the drawing, it will be apparent the device includes a hollow open-ended body 10 rectangular in transverse section and thus providing a flow passage 11. The body 10 has flanges 12 so that the device may be secured by bolts 13 in an operative position between the flanged down-flow fuel mixture outlet 2 of a conventional carburetor and a conventional intake manifold 14, as shown in Fig. 1. The usual throttle butterfly valve member designated 15 is operable in the outlet 2.

Suction responsive valve means is arranged for operation in the passage 11. Said means includes a butterfly valve member 16 having a pivot 17 supported by the body 10, and a flapper 18 having a pivot 19 also supported by the body 10. The pivot 17 is offset slightly with respect to the longitudinal axis of the passage 11. The portion 20 of the valve member 16 extending on one side of the pivot 17 is smaller than the portion 21 extending on the opposite side of the pivot 17. When the valve member 16 is in its fully

2

closed position, it is inclined in contact with the opposite side walls of the passage 11, as shown in dotted lines in Fig. 3. In the operation of the governor, the valve member 16 never reaches this position. The valve member 16 is shown in full lines in its fully open position. The flapper 18 projects only at one side of the pivot 19. The pivot 19 is arranged near one wall of the passage 11 slightly below the pivot 17.

10 In order to cause the valve member 16 to move in unison with the flapper 18, suitable motion transmission means is provided within a housing 22 secured to or formed integral with the body 10. Said means comprises an arm 23 fast on the pivot 17, an arm 24 fast on the pivot 19, and a link 25 having its opposite ends pivotally connected, as at 26 and 27, respectively, with the arms 23 and 24.

In order to check the closing movement of the 20 flapper 18 from its fully open position, there is provided a detent consisting of an arm 28 fast on the pivot 19. A roller 29 on the free end of the arm 28 cooperates with a tension spring 30. The spring 30 is bent and formed from a strip of 25 spring metal to provide an attaching portion 31 and a rebent resilient portion 32 in continuation of the portion 31, said portion 32 having a crimp 33. The spring 30 is arranged within, and its portion 31 is secured to the housing 22, as at 34. A screw 35 carried by the housing acts on the resilient portion 32 to adjust the tension of the spring. This spring checks the flapper 18 for attaining quick acceleration of the engine to bring it up to the desired speed before coming 35 unto the load.

In order to cause the return movement of the 40 flapper 18 there is provided a reaction leaf spring 36 which has one end secured to the housing 22, as at 37, and its opposite end bears on the roller 29. The tension of the spring 36 is regulated by means of a notched abutment 38 carried by a nut 39 threaded on a screw 40 disposed horizontally of the housing 22. One end of the screw 40 is swivelled in a bearing 41 on the housing 45 interiorly thereof, and the opposite end of the screw projects loosely through the housing and has a knurled knob 42 secured thereto exteriorly of the housing. A spring pressed ball 43 carried 50 by the knob 42 cooperates with a circular series of depressions 44 in the housing to function as a detent to prevent unintentional rotation of the screw 40. A fixed stop 45 on the screw 40 limits the movement of the abutment 38 in the spring 55 releasing direction. A collar 46 on the screw 40

cooperates with the knob 42 to prevent axial movement of the screw.

The housing 22 has a removable plate 47 which affords access to the parts within the housing.

Referring now to the valve member 16 and the flapper 18. This flapper is suction responsive and always controls the movement of the valve member 16. The flapper 18 is responsive to any variation of the suction, balancing the velocity suction action against the valve member 16 subject to the action of the spring 36. The valve member 16 controls or regulates the volume or amount of incoming fuel mixture through the passage 11 to the intake manifold to the engine cylinders, according to the engine demand for the power output. The engine suction acts on the flapper 18 and draws it laterally and down or inward causing a corresponding closing movement of the butterfly valve member 16. The spring 36 reacts to cause the return or opening movement of the flapper 18 and valve member 16 through the intervention of the parts 29, 28, 24, 25, 23, 19 and 18.

The offsetting of the valve member 16 with its small and large portions 20 and 21, respectively, checks or stops any tendency of the valve member 16 to be brought into any balanced position by suction action on the valve member 16 itself. The suction pull is stronger on the large portion 21 tending always to make the valve member 16 to come to an open unbalanced position.

The operation of the governor is as follows. When the engine is idling with the throttle valve member 15 in idling position, the flapper 18 and the valve member 16 are checked in their fully open or neutral positions by the springs 30 and 36, due to decreased suction on the flapper 18. As the throttle valve member 15 is opened gradually or suddenly, to accelerate the engine, there is an increased velocity of the fuel mixture as well as even suction action in the passage 11. The added spring tension exerted by the spring 30 on the roller 29 releasably resists the tendency of the flapper 18 to move laterally and down or inward from the fully open position, until the suction induced on the flapper 18 is greater than pressure exerted by the springs 30 and 36, whereupon the spring 30 releases the roller 29 which acts on the spring 36, according to the governing adjustment of the parts. Thus, the engine may be quickly accelerated, until it is to deliver the governed power demand of the engine. As the flapper 18 is moving from the fully open position by the increased velocity of the fuel mixture with corresponding increase of suction and speed of the engine, the valve member 16 is closing. This closing of the valve member 16 increases the velocity of the fuel mixture to the engine to the governed horsepower demand.

From the foregoing, it will be understood the governor of the present invention has a relatively light and critical spring action for full control of the suction without build-up and full control of the fuel mixture to the engine for accelerating, pulling and the power demands of the engine. It also enables a full range of adjustments from the lowest to the highest governed speeds.

I claim:

1. In a device for governing the amount of air

and fuel mixture to an internal combustion engine, a body having a flow passage extending therethrough, a valve member pivotally mounted on said body and having closing and opening movement in said passage, a suction responsive member pivotally mounted on said body and operable in said passage, means connecting said valve member with said suction responsive member so that the former moves in unison with the latter, checking means connected with the suction responsive member to normally retain it in such position that the valve member is in a fully open position subject to closing movement in response to suction action exceeding a pre-determined degree, said checking means consisting of an arm connected with the suction responsive member, said arm having a roller, and a crimped spring which coacts with said roller, and resilient means which cooperates with the checking means to cause the return movement of the suction responsive member and the valve member connected therewith.

2. In a device for governing the amount of air and fuel mixture to an internal combustion engine, a body having a flow passage extending therethrough, a valve member pivotally mounted on said body and having closing and opening movement in said passage, a suction responsive member pivotally mounted on said body and operable in said passage, means connecting said valve member with said suction responsive member so that the former moves in unison with the latter, checking means connected with the suction responsive member to normally retain it in such position that the valve member is in a fully open position subject to closing movement in response to suction action exceeding a pre-determined degree, and resilient means which cooperates with the checking means to cause the return movement of the suction responsive member and the valve member connected therewith, said checking means consisting of an arm connected with the suction responsive member, said arm having a roller, and a crimped spring which coacts with said roller, and resilient means consisting of a leaf spring bearing on said roller.

3. In a device as set forth in claim 1, and means for regulating the tension of the resilient means.

4. In a device as set forth in claim 2, an abutment contacting the resilient means, and screw means engaged with said abutment to change the position of the abutment for regulating the tension of said resilient means.

HAROLD T. SNELL.
